VAMP FOR SHOES.

1,333,213.

Specification of Letters Patent.

Patented Mar. 9, 1920.

Application filed June 4, 1919. Serial No. 301,605.

To all whom it may concern:

Be it known that I, GEORGE E. MUSEBECK, a citizen of the United States, and resident of Milwaukee, in the county of Milwaukee and State of Wisconsin, have invented new and useful Improvements in Vamps for Shoes, of which the following is a description, reference being had to the accompanying drawings, which are a part of this specification.

Heretofore in the manufacture of shoes the vamp has been given its form by stretching it over a last and then tacking it to the bottom of the last. By thus stretching the vamp to form over the last, which is done either by hand or by the so-called nigger-head machine, it frequently happens that the vamp is torn where the throat portion joins the wings, which results in the loss of both labor and material. This stretching operation also throws the vamp out of shape generally and due to the unequal texture inherent in the leather frequently produces objectionable creases detracting from the appearance of the shoe and uncomfortable to the wearer. Furthermore, in the vamps as heretofore made, much leather is wasted in the stretching and trimming of the vamp. To overcome these difficulties I have provided a vamp blank in which the throat portion thereof is set to substantially conform to the shape of the last prior to placing the vamp blank upon the last. A vamp blank of this character preserves its shape and avoids the use of excessive force to stretch it to shape over the last and thus prevents splitting, tearing or weakening of the vamp where the throat portion joins the wings, and also enables the use of a narrow pattern, with a saving of leather. It has the further advantage of preventing distortion of the tip line of the vamp where separate tips are used, though it is to be understood that the invention is applicable to vamps having the full tip. The setting of the throat portion to conform with the last is accomplished by molding the throat portion of the vamp, preferably under the application of heat, prior to placing it on the last. This initial preformed condition of the vamp blank obviates the use of great force generally employed to draw the vamp down to the wood when it is placed on the last.

The invention further consists in the several features hereinafter set forth and more particularly defined by claims at the conclusion hereof.

In the drawings: Figure 1 is a view of the vamp blank; Fig. 2 is a perspective view of the completed vamp blank; Fig. 3 is a sectional view through the completed vamp blank.

The vamp blank shown in the drawings is one to which a separate tip is to be attached but it is to be understood that the tip may be made integral with the rest of the vamp blank where desired. The vamp blank 4 is cut out of a single piece of leather to provide a front portion 5, wings 6, and a throat portion 7, which is that part between the full line 8 and the dotted line 9, said throat portion meeting the wings at 10. Where the vamp is used for high shoes prick punch marks 12 are made in the blanks as usual prior to its being incorporated in the shoe and serve as a guide to the operator in stitching the upper to the vamp. Heretofore vamps have been made by cutting out a vamp blank similar to that shown in Fig. 1 and giving this vamp blank its form by stretching it over a last and tacking it down to the bottom of the last. This stretching operation is either done by hand or by a so-called nigger-head machine, and frequently results in the splitting, tearing or weakening of the vamp at the points 10.

By the present invention the throat portion 7 of the finished vamp blank 11, shown in Figs. 2 and 3, is formed prior to disposal on the last by molding this throat portion to substantially conform to the shape of the last, the molding operation being confined or localized to the throat portion so that the wings will not be stretched out of proper form and so that the indicating marks, if used, will not be displaced. This molding operation may be carried out in various ways, one way being to mold the throat portion into shape between two properly shaped dies, accompanied by heating of the throat portion so as to set it to the desired shape. A blank of this character preserves its shape and avoids the use of excessive force many times necessary to shape the vamp over the last and thus prevents any splitting, tearing or weakening of the vamp, maintains the

indicating marks in proper position and allows the use of a narrower pattern with a saving of leather.

I am aware that vamp blanks have been 5 previously subjected to a so-called creasing process by a machine which draws the vamp down between two pressing members, the drawing member engaging the vamp at the central portion thereof, but such a process 10 creates a stretching of the vamp throughout its entire central portion. This stretching or creasing of the vamp results in several disadvantages: First, the stretching of the vamp throws the wings of the vamp out of 15 line with the original pattern so that the wings have to be trimmed down prior to placing the vamp on the last, which, of course, involves expense of labor and loss of material; second, due to the fact that the 20 stretching operation is not only produced at the throat of the vamp but also through the entire central portion thereof, the tip line of the vamp, where additional tips are used, is distorted which produces difficulties in 25 attaching the tip to the vamp and also necessitates trimming; third, this creasing operation does not prepare the vamp blank to

substantially fit the last and the real forming is done upon the last and is therefore open to the objections previously set forth; 30 and, lastly, the stretching of the vamp throws out the proper location of the prick punch marks so that the uppers are not properly stitched in place where the vamps 35 are used on high shoes.

It is to be understood that this invention is not limited to any specific form or arrangement of parts, except in so far as said limitations are specified in the claims.

What I claim as new and desire to secure 40 by Letters Patent is:

1. A vamp blank expanded solely in the throat portion.
2. A vamp blank expanded solely in the throat portion to substantially last conforming shape prior to its being placed on the last. 45

In testimony whereof, I affix my signature, in presence of two witnesses.

GEORGE E. MUSEBECK.
